ELECTRIC LANTERN

Chan Pak Chun, Hong Kong, British Crown Colony

Application April 6, 1959, Serial No. 55,351

Term of patent 14 years

(Cl. D48—24)

Fig. 1 is a side elevational view of an electric lantern showing my new design;

Figure 2 is a side elevational view thereof with the blinker light in raised position;

Figure 3 is a top plan view of the lantern as shown in Figure 2;

Figure 4 is a front elevational view of the lantern as shown in Figure 1; and

Figure 5 is a rear elevational view of the lantern as shown in Figure 1.

The side of the electric lantern not shown is substantially the same in appearance as the side shown.

I claim:

The ornamental design for an electric lantern, substantially as shown and described.
